(57) **CLAIM**

We claim the ornamental design for a mobile computing support system, as shown and described.

DESCRIPTION

FIG. 1 is a front perspective view of a mobile computing support system showing our design;

FIG. 2 is a bottom view thereof;

FIG. 3 is a top view thereof;

FIG. 4 is a right side view thereof;

FIG. 5 is a left side view thereof;

FIG. 6 is a front view thereof; and,

FIG. 7 is a rear view thereof.

The broken lines shown in the figures show portions of the mobile computing support system that form no part of the claimed design.
